UNITED STATES PATENT OFFICE

156,361

SERVING CART

James Joseph McMahon, Sydney, New South Wales, Australia

Application October 16, 1947, Serial No. 141,932

Term of patent 3½ years

(Cl. D14—3)

To all whom it may concern:

Be it known that I, James J. McMahon, a citizen of the Dominion of Australia, residing in Sydney, New South Wales, Australia, have invented a new, original, and ornamental Design for a Serving Cart, of which the following is a specification, reference being had to the accompanying drawing, forming part thereof:

Fig. 1 is a top plan view of the serving cart showing my new design.

Fig. 2 is a side elevational view thereof.

The shading indicates contrasting appearance.

I claim:

The ornamental design for a serving cart, substantially as shown and described.

JAMES JOSEPH McMAHON.
